SEALED POWDER CONTAINER

John J. O'Connor, New York, N. Y.

Application August 2, 1935, Serial No. 34,461

7 Claims. (Cl. 132—82)

The present invention relates to a powder container adapted to contain toilet powder, and has for an object to provide a small compact device adapted to fit in a lady's hand-bag, pocket-book or the like, and not only occupy but relatively small space and afford a ready and convenient means for access to the powder, but which is of such construction that the powder is sealed in the container and cannot sift or seep out of the container into the hand-bag or pocket-book.

Another object of the present invention is to provide a powder container of this character which may be conveniently held in the hand and operated to open the container, and wherein in the container is provided with a sifting opening so that the powder may be sifted onto a powder puff, handkerchief or the like for use and in the desired small quantity.

Another object of the invention is to provide a powder container of this character which is of an economical and practical construction not only from the point of manufacture but also with reference to its use and handling, and a container which readily lends itself to various artistic constructions and colorings so that the latter may be ornamented in various ways to produce an attractive and pleasing article.

A further object of the present invention is to provide a container of this character with a closure constructed to slide by a slight pressure of the thumb or finger and which is maintained in sealed or taut position when closed by a novel spring structure and arrangement of parts.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a side elevation of a powder container constructed according to the present invention, the container being closed.

Figure 2 is an end elevation of the same.

Figure 3 is a side elevation of the construction in open position and held in the hand with the sifting opening uppermost.

Figure 4 is a similar view but with the container turned over with the sifting opening downward and showing powder being sifted from the container.

Figure 5 is an enlarged longitudinal section taken through the container in closed position.

Figure 6 is a similar view of the container in

open position and inverted for delivering powder therefrom.

Figure 7 is a transverse section on the line 1—7 of Figure 6 and through the sifting button or projection.

Figure 8 is a similar view taken on the line 8—8 of Figure 6 and looking toward the spring carrying head of the container.

Figure 9 is a perspective view of the parts of the container separated and in their relative positions ready for assembling.

Figure 10 is a detail perspective view of a modified construction of container.

Figure 11 is a fragmentary enlarged section taken through one end of the same, showing the 15 slidable closure on the end of the container.

Figure 12 is an outer end elevation of the same, the slide button shank being shown in section.

Figure 13 is an enlarged sectional view through 20 one end of the container showing a further modification in its construction, and

Figure 14 is an outer end view of the same.

Referring now to the drawings and first to the form of the invention disclosed in Figures 1 25 to 9 inclusive, the container comprises a cylindrical body portion 20 which may be of metal or other suitable material and which is of relatively small size so as to readily fit into a handbag, pocket-book or the like which at the same 30 time is capable of carrying a desired quantity of powder to be used from time to time. The cylindrical body 20 is open at opposite ends and is closed by end heads 21 and 22 which may be of the internal flange type with the flanges adapted to fit with the desired frictional contact against the inner wall of the cylinder 20, and the head 22 is used as the removable closure adapted to be opened at times for filling the cylindrical body portion 20.

At one side the body portion 20 is provided with an outlet or sifting opening 23 which may be constructed in various ways, such as by cutting or stamping, and which is preferably cylindrical and provided with an intermediate cross 45 bar 24 dividing the opening 23 into adjacent semi-circular portions to break up the body of powder adapted to be poured or sifted through the opening 23 when the body 20 is overturned and given the necessary vibration.

The opening 23 thus insures a free and widely dispersed stream of powder from the opening. In the same side of the body portion 20, the latter is provided with a longitudinal guide slot 25 which is in longitudinal alignment with the open- 55

ing 23 and adapted to receive therethrough the shank 26 of a slide button 27 which is carried by a slide or shutter 28 disposed exteriorly against the side of the body portion 20. The slide 28 5 may be of metal or the like adapted to have flat surface contact with the exterior surface of the body 20 and which is of suitable length to project over the opening 23 and close it when the slide 28 is shifted toward one end of the container, as shown in Figure 5, and as shown in Figure 6, to open the opening 23 when the slide 28 is retracted.

The guide slot 25 is of sufficient length to admit of the full opening and closing movements 15 of the slide 28 and to limit further movements of the slide when the latter reaches its extreme open and closed position. The slide button 27 is of sufficient size only to admit of the required contact with the thumb or finger to effect the 20 movement of the slide 28 and may be given any suitable configuration which will accomplish the purpose.

The shank 26 of the slide button is provided with a slot 29 extending therethrough from side 25 to side and which is of suitable size to freely receive therethrough a spring 30 of wire or the like which is disposed within the container body 20. The free end of the spring 30 is offset upwardly to provide a bearing finger 31 for engagement against the inner wall of the container body 20 opposite to the slide 28 and the spring 30 is given an inherent resiliency for springing inward and for tension against the shank 26 for drawing the slide button 27 and the slide 28 tight 30 against the side of the container.

The spring 30 thus holds the slide 28 frictionally against the container and insures the sealing of the slide thereagainst so that powder within the container cannot readily escape there- 40 from into the hand-bag or pocket-book.

The body portion of the spring 30 when under tension, as shown in Figure 5, is substantially parallel to the adjacent wall of the container so that the shank 26 of the slide button is free 45 to be shifted lengthwise of the guide slot 25 and the desired tension is maintained at all times on the shank 26.

The other end of the spring 30 is provided with a suitable supporting frame 32 which, as 50 shown in Figures 8 and 9, may be triangular in shape and which is adapted to be compressed into the flange of the fixed head 21 of the container. This frame 32 is adapted to hold the spring 30 firmly in place.

As may be readily seen from Figure 9, the powder container is of relatively simple construction and may be easily assembled. The slide 28 is fitted against the side of the cylindrical body portion 20, the shank 26 of the slide button 27 60 is now inserted through the opening 33 at the intermediate portion of the slide 28 and through the guide slot 25 and held in such position while the finger 31 of the spring 30 is inserted into the end of the container body 20 and threaded 65 through the slot 29 in the stud or shank 26.

The offset portion of the spring 30 moves the finger 31 against the inner wall of the container and also forces the body portion of the spring 30 against the inner wall of the slot 29 so as to 70 place the stud or shank under tension. At the same time the spring 30 is introduced into the body portion 20 and the head 21 is forced into closed position. This head 21 may be permanently secured to the end of the body portion 20 75 or may simply be given a tighter fit therein than

the head 22. The head 22 is adapted to be removed by slight pressure from the end of the container so that the latter may be filled from time to time with powder.

The device may be made in different sizes, of different materials and readily lends itself to different types and designs of ornamentation so that the article may be made in different grades and may be sold as various grades of merchandise. 10

As shown in Figures 10, 11, and 12, the container body 34 may be given a relatively flat or oval form in cross section and the slide 35 may be in the form of a flat strip disposed against one head 36 of the container. The head 36 may have 15 the sifting or outlet opening 37 therein and also the guide slot 38.

The slide 35 carries the slide button 27 with its shank 26 as above described for receiving therethrough a spring 39. The spring 39 may 20 be turned over at one end 40, and this turned over portion may be secured in any suitable manner to the flange of the head 36. The other end of the spring is provided with an offset finger 41 similar to the finger 31 in the preferred form 25 to give the spring 39 the desired tension against the shank 26.

As shown in Figure 12 the shank 26 may be rectangular in cross section so as to fit the guide slot 38 and hold the slide button 27 and the slide 30 35 from turning out of line with the outlet opening 37.

In the modification shown in Figures 13 and 14, the end head 42 of the container body 34 may be provided with a recess or countersink 43 in its outer side for the reception of the slide 35 and this countersink is of sufficient length to admit of the free opening and closing movements of the slide 35. Otherwise the construction is similar to that shown in Figures 10, 11, and 12. 35

It is obvious that various changes and modifications may be made in the details of construction and design of the above specifically described embodiment of this invention without departing from the spirit thereof, such changes and modifications being restricted only by the scope of the following claims. 40

What is claimed is:—

1. A powder container comprising a body portion having an outlet opening therein and having a guide slot in line with the outlet opening, a slide engaging the outer side of the container body for closing said opening and slot, a slide button carried by the slide and having a shank engaging through said guide slot, and a spring 50 fixedly mounted in the container body and loosely engaging the shank of said slide button to yieldingly hold the slide against the container body. 55

2. A powder container comprising a body portion having in one wall an outlet opening and a 60 guide slot spaced from the outlet opening, a slide fitted against the exterior face of said wall, a slide button carried by the slide and having a shank projecting through said guide slot and said shank having a slot therethrough, and a spring 65 fixedly carried in the body portion and engaging through the slot in said shank for drawing the shank inwardly and yieldingly holding the slide against said wall of the body portion, said slide button adapted to be pressed in one direction for shifting the slide to uncover said outlet opening and in an opposite direction for shifting the slide into position to cover said outlet opening. 70

3. A powder container comprising a cylindrical body open at opposite ends and having in one 75

side a longitudinal slot and an outlet opening spaced from one end of the slot, a slide fitted to the exterior surface of said side of the body portion for covering the slot and the opening, 5 heads fitting on the opposite ends of said body portion to close the same, a spring carried by one of said heads and extending lengthwise in said body portion and in spaced relation to said side thereof, and a slide button carried by the slide 10 and having a shank projecting through said guide slot, said shank having a slot therein for the reception of said spring, said spring adapted to yieldingly urge the shank and slide button inwardly to hold the slide in sealed engagement 15 against said side of the body portion.

4. A powder container comprising a cylindrical body portion, heads carried on the opposite ends of the body portion, one of said heads being removable for introducing powder into the body 20 portion, a spring in the body portion having a frame at one end frictionally engaging in a head of said body portion to hold the spring in position, a slide fitted to the outer surface of the body portion, and a slide button carried by the slide 25 and having a shank extending inwardly through said guide slot and provided with an opening for the reception of said spring, whereby said spring yieldingly holds the slide button and the slide against the side of said cylindrical body, said 30 guide slot admitting of the shifting of the slide with the shank into one position for opening the outlet opening and in another position for closing said outlet opening.

5. A powder container comprising a relatively 35 flat body portion substantially oval in cross section and having closure heads at opposite ends, one of said heads having a guide slot therein

and an outlet opening spaced from the slot, a slide fitting against the outer side of said head to close the slot and the opening, a spring fixedly carried in said head, and a slide button mounted on the slide and having a shank projecting through said 5 guide slot and engaging said spring to yieldingly hold the slide in sealed engagement against the head.

6. A powder container comprising a relatively flat body portion substantially oval in cross section and having closure heads at opposite ends, one of said heads having a guide slot therein and an outlet opening spaced from the slot, a slide fitting against the outer side of said head to close the slot and the opening, a spring carried in said 10 head, and a slide button mounted on the slide and having a shank projecting through said guide slot and engaging said spring to yieldingly hold the slide in sealed engagement against the head, the shank of said slide button having opposed 15 flat sides adapted to engage the sides of the guide slot to hold the shank and the slide from turning out of line with said outlet opening.

7. A powder container comprising a body portion having a head at its end, said head having a 20 depressed portion therein and said depressed portion having a guide slot and an outlet opening therethrough, a slide movably mounted in said depressed portion to cover the slot and the opening, a spring fixedly mounted in the body portion, 25 and a slide button carried by the slide and having a shank projecting inwardly through said guide slot and engaging the spring for frictionally holding the slide in the depressed portion of the head to seal the slot and the opening. 30 35

JOHN J. O'CONNOR.
